UNITED STATES PATENT OFFICE.

CHARLES WIRT, OF CHICAGO, ILLINOIS.

DESIGN FOR AN INSULATOR-BRACKET.

SPECIFICATION forming part of Design No. 21,380, dated March 8, 1892.

Application filed January 4, 1892. Serial No. 417,019. Term of patent 3½ years.

To all whom it may concern:

Be it known that I, CHARLES WIRT, a citizen of the United States, residing at Chicago, in the county of Cook and State of Illinois, 5 have invented a new and original Design for Brackets for Electric Wires, of which the following is a specification.

My invention relates to designs for electric-wire brackets or for brackets for supporting 10 insulators for electric wires. It is illustrated in the accompanying drawings, wherein—

Figure 1 is a side view of the bracket. Fig. 2 is a plan view thereof.

The same parts are indicated by the same 15 letters in both figures.

B is a cylindrical portion; D, a flat plate; A, a flat arm projecting from the cylindrical portion; F, a curved part connecting the flat plate and arm; G G, flanges above and below the arm and the curved portion and extending from the flat plate to the cylindrical part. 20

I claim—

The design for brackets, substantially as shown and described.

CHARLES WIRT.

In presence of—

FRANCIS W. PARKER,
VIRGINIA WILLEY.
